[57] CLAIM

The ornamental design for boat and utility trailer stand or the like, substantially as shown and described.

DESCRIPTION

FIG. 1 is a front elevational view of the boat and utility trailer stand or the like showing my new design;

FIG. 2 is a right side elevational view thereof;

FIG. 3 is a left side elevational view thereof;

FIG. 4 is a rear elevational view thereof;

FIG. 5 is a top plan view thereof;

FIG. 6 is a bottom plan view thereof;

FIG. 7 is a front elevational view of the second embodiment of a boat and utility trailer stand or the like showing my new design;

FIG. 8 is a right side elevational view of FIG. 7;

FIG. 9 is a left side elevational view thereof;

FIG. 10 is a rear elevational view thereof;

FIG. 11 is a top plan view thereof; and

FIG. 12 is a bottom plan view thereof.
